UNITED STATES PATENT OFFICE.

HERBERT S. HUMPHREY, OF KALAMAZOO, MICHIGAN.

WATER-HEATER.

No. 928,311.

Specification of Letters Patent.

Patented July 20, 1909.

Application filed January 15, 1909. Serial No. 472,461.

To all whom it may concern:

Be it known that I, HERBERT S. HUMPHREY, a citizen of the United States, residing at Kalamazoo, county of Kalamazoo, 5 and State of Michigan, have invented certain new and useful Improvements in Water-Heaters, of which the following is a specification.

This invention relates to improvements in 10 water heaters.

The main objects of this invention are: First, to provide in a water heater an improved valve mechanism whereby the fuel valve is controlled to maintain a comparatively even temperature on the water drawn, although its volume varies. Second, to provide in a water heater an improved valve mechanism for automatically controlling the temperature of the water drawn from the 20 heater, and also the temperature of the water in the heater when the drawing of the water ceases. Third, to provide in a water heater, an improved valve mechanism whereby the fuel valve is automatically controlled by the 25 water drawn from the heater and by the thermostat which coact one with the other. Fourth, to provide in a water heater an improved pilot flashing means whereby the pilot is automatically controlled by the 30 water.

Further objects, and objects relating to structural details, will definitely appear from the detailed description to follow.

I accomplish the objects of my invention 35 by the devices and means described in the following specification.

The invention is clearly defined and pointed out in the claims.

A structure embodying the features of my 40 invention is clearly illustrated in the accompanying drawing, forming a part of this specification, in which—

Figure 1 is a detail elevation of a water heater structure embodying the features of 45 my invention, a portion of the heater casing being broken away to better show the arrangement of the parts. Fig. 2 is an enlarged detail vertical section through the valve mechanism, taken on a line corresponding to line 2—2 of Fig. 1. Fig. 3 is an 50 enlarged detail, partially in vertical section,

of a line corresponding to line 3—3 of Fig. 2. Fig. 4 is an enlarged detail section taken on a line corresponding to line 4—4 of Fig. 2, showing details of the pilot valve and its connection. Fig. 5 is a detail section taken on a line corresponding to line 5—5 of Fig. 2.

In the drawings, similar reference characters refer to similar parts throughout the several views, and the sectional views are taken looking in the direction of the little arrows at the ends of the section lines.

Referring to the drawing, the heater 1 is of the coil type, the same being provided with a plurality of coils 2, arranged in vertical series. The casing of the heater is preferably double walled, as illustrated, to prevent radiation. The burners 3 are arranged in the base of the heater below the coils. The water supply in the structure illustrated, is connected to the heater through the valve casing 4, which is provided with a water inlet 5 connected to the water supply pipe 6, and with a discharge 7 connected to the heater through the inlet pipes 8 at the upper ends of the 70 heater coils. The valve casing is also provided with a hot water inlet 9 and a hot water discharge 10, the discharge being controlled by a regulating valve 11. The hot water discharge 10 is connected to the house 80 system or to a delivery pipe, as 12, which is provided in the structure illustrated with a faucet, as 13, the faucet being illustrated only to indicate the operation of the heater.

The hot water inlet or passage 9 is connected to the discharge pipe 14 from the lower end of the heater coils, preferably through the thermostat tube 38. The hot water inlet 9 is preferably connected to the cold water discharge 7 through a circulation port 15, so that when the circulation port 15 is open the water may circulate through the heater and the thermostat, this structure of the valve casing being substantially that illustrated in my application for Letters Patent 95 filed November 23, 1908, Serial No. 464,121.

The water inlet valve 16 is preferably of the piston type and is adapted to be automatically opened by the pressure of the inlet water when water is drawn from the heater, thereby reducing the pressure within the 100 heater or system. On the stem 17 of the

valve 16 I arrange a circulation valve 18. This circulation valve 18 is loosely mounted on the stem and is yieldingly held against the rest 19 thereon by means of the coiled spring 20. This spring 20 is preferably arranged about the stem, as illustrated, its upper end bearing against the valve 16, and its lower end engaging the valve 18. The rest 19 is preferably made adjustable so that the valve 18 can be adjusted to seat prior to the opening of the inlet valve 16. A further advantage of this adjustment is that it obviates the necessity of great care in the fitting of the parts.

15. On the section 21 of the valve stem, I arrange a return spring 22, which is compressed by the opening of the valve 16 and expands to return the valve to its seat. The spring is arranged in a chamber 23, is in the form of a cylindrical cap-like extension of the valve casing, and which cap can be removed without removing the main cap of the valve casing, thus permitting the adjustment or renewal of the spring 22 without disturbing the packing for the main cap of the valve casing. The arrangement of these valves described is substantially that of my application before referred to.

The gas valve casing 24 is provided with 30 an inlet 25 connected to the gas supply, not here illustrated, and with a discharge 26 which is connected through the pipe 27 to the burners 3. The fuel valve 28 is held yieldingly against its seat by means of the 35 coiled spring 29. Operating connections are provided for the water inlet valve 16, and the thermostat to the stem 30 of the fuel valve. This operating connection in the structure illustrated consists of the movable member 40 31, which is preferably tapered and pivotally mounted on the stem of the water actuated valve 16 by means of the pivot 16'. The thermostat actuated member or lever 32 is arranged to engage this member 31, the lever 45 being mounted on a fulcrum or pivot 33 on the gas valve casing 24. This lever 32 is engaged by a lever 34, which is fulcrumed at 35 to be engaged by the thermostat member 36, which is arranged in and connected to the 50 tubular thermostat member 37, which is arranged in the thermostat tube 38. The structure and action of the thermostat will be readily understood.

The movement of the movable member 31 55 on which the thermostat and the water actuated valve act, is imparted to the fuel valve stem 38 preferably through the links 39 and 40, the link 39 being pivoted to the valve stem, the link 40 to the post 41 on the yoke 50 42, by which the valve casings 4 and 24 are connected. The links 39 and 40 are provided with a bearing member 43 for the movable member 31, the links being pivotally connected thereto by means of the pivot 44.

55. The bearing member 44 is provided with a

downwardly extending stem 45 which is arranged through a slot 46 in the yoke so as to be guided thereby. The bearing member and links are held normally upward or collapsed by means of the coiled spring 47, one end of which engages a shoulder, as 48, on the stem 45, and the other rests upon the yoke 42.

The pilot burner 49, is connected by the pipe 50 to a passage 51 in the valve casing 24, 75 see Fig. 4. The normal flame of the pilot is controlled by a valve 52, while the flashing flame is controlled by the valve 53 and this valve is preferably mounted or carried by the stem 30 of the main fuel valve, as is illustrated. This pilot is further controlled by a valve as 53, which may be adjusted to entirely cut off the pilot when desired, and to regulate the size of the flashing flame. The valve stem is preferably provided with a lost motion connection with a fuel valve, so that the pilot valve is opened prior to the opening of the fuel valve. This I accomplish in the structure illustrated by providing a slip connection for the fuel valve and its stem. This insures the opening of the pilot prior to the opening of the fuel valve, thereby flashing the pilot. By this connection for the operation of the fuel valve, it is opened according to the amount of water drawn from the 95 heater and according to the temperature of that water, as the thermostat also acts upon the fuel valve. The temperature of the water is thereby held at a substantially constant point, notwithstanding the variations in the amount of water drawn, and in the present structure, the normal temperature of the water in the heater is maintained comparatively constant through the action of the thermostat, that is the parts may be so adjusted that the temperature of the water in the heater is maintained at a low point normally and as soon as water is drawn it is increased to a desired point and maintained approximately at that point throughout variations in the volume of water drawn from the heater.

110 While this construction illustrated is found to be very satisfactory I am aware that it can be very considerably varied without departing from my invention, and I desire to be understood as claiming the same broadly as well as specifically, as I have herein illustrated, and described.

115 Having thus described my invention, what I claim as new and desire to secure by Letters Patent is:

1. The combination with a water heater, of a burner therefor; a pilot for said burner; a water inlet valve; a circulation valve adapted to be automatically closed when said water inlet valve is opened and opened when said water inlet valve is closed; a thermostat connected to said heater; a fuel valve; a fuel valve stem; a pilot valve on 120

125

130

said fuel valve stem, arranged so that said pilot valve is opened to flash the pilot prior to the opening of said fuel valve; operating connections for said thermostat and water inlet valve to said fuel valve stem, comprising a lever actuated by said thermostat, a pair of links, one of said links being pivotally connected to said fuel valve stem, and the other to a fixed support; a bearing member to which said links are pivotally connected; and a tapered member pivotally mounted on said water valve stem to be reciprocated thereby between said thermostat actuated lever and said bearing member.

15. 4. The combination with a water heater, of a burner therefor; a pilot for said burner; a water inlet valve; a circulation valve adapted to be automatically closed when said water inlet valve is opened and opened when said water inlet valve is closed; a thermostat connected to said heater; a fuel valve; a fuel valve stem; a pilot valve on said fuel valve stem, arranged so that said pilot valve is opened to flash the pilot prior to the opening of the said fuel valve; operating connections for said thermostat and water inlet valve to said fuel valve stem, comprising a lever actuated by said thermostat; a pair of links, one of said links being pivotally connected to said fuel valve stem, and the other to a fixed support; a bearing member to which said links are pivotally connected; and a member pivotally mounted on said water valve stem to be reciprocated thereby between said thermostat actuated lever and said bearing member.

3. The combination with a water heater, of a burner therefor; a water inlet valve; a circulation valve adapted to be automatically closed when said water inlet valve is opened and opened when said water inlet valve is closed; a thermostat connected to said heater; a fuel valve; a fuel valve stem; operating connections for said thermostat and water inlet valve to said fuel valve stem, comprising a lever actuated by said thermostat, a pair of links, one of said links being pivotally connected to said fuel valve stem, and the other to a fixed support; a bearing member to which said links are pivotally connected; and a tapered member pivotally mounted on said water valve stem to be reciprocated thereby between said thermostat actuated lever and said bearing member.

55. 4. The combination with a water heater, of a burner therefor; a water inlet valve; a circulation valve adapted to be automatically closed when said water inlet valve is opened and opened when said water inlet valve is closed; a thermostat connected to said heater; a fuel valve; a fuel valve stem; operating connections for said thermostat and water inlet valve to said fuel valve stem, comprising a lever actuated by said thermostat, a pair of links, one of said links being pivotally connected to said fuel valve stem, and the other to a fixed support; a bearing member to

pivotally connected to said fuel valve stem, and the other to a fixed support; a bearing member to which said links are pivotally connected; and a member pivotally mounted on said water valve stem to be reciprocated thereby between said thermostat actuated lever and said bearing member.

5. The combination with a water heater, of a burner therefor; a pilot for said burner; a water inlet valve; a circulation valve adapted to be automatically closed when said water inlet valve is opened and opened when said water inlet valve is closed; a thermostat connected to said heater; a fuel valve; a fuel valve stem; a pilot valve on said fuel valve stem, arranged so that said pilot valve is opened to flash the pilot prior to the opening of said fuel valve; and operating connections for said thermostat and water inlet valve to said fuel valve stem, including a tapered movable member through which said inlet valve and thermostat are each arranged to act.

6. The combination with a water heater, of a burner therefor; a pilot for said burner; a water inlet valve; a circulation valve adapted to be automatically closed when said water inlet valve is opened and opened when said water inlet valve is closed; a thermostat connected to said heater; a fuel valve; a fuel valve stem; a pilot valve on said fuel valve stem, arranged so that said pilot valve is opened to flash the pilot prior to the opening of said fuel valve; and operating connections for said thermostat and water inlet valve to said fuel valve stem including a movable member through which said inlet valve and thermostat are each arranged to act.

7. The combination with a water heater, of a burner therefor; a water inlet valve; a circulation valve adapted to be automatically closed when said water inlet valve is opened and opened when said water inlet valve is closed; a thermostat connected to said heater; a fuel valve; and operating connections for said thermostat and water inlet valve to said fuel valve; including a tapered movable member through which said inlet valve and thermostat are each arranged to act.

8. The combination with a water heater, of a burner therefor; a pilot for said burner; a water-actuated member; a thermostat connected to said heater; a fuel valve; a fuel valve stem; a pilot valve on said fuel valve stem, arranged so that said pilot valve is opened to flash the pilot prior to the opening of said fuel valve; operating connections for said thermostat and water-actuated member to said fuel valve stem, comprising a lever actuated by said thermostat, a pair of links, one of said links being pivotally connected to said fuel valve stem, and the other to a fixed support; a bearing member to

which said links are pivotally connected; and a tapered member carried by said water actuated means to be reciprocated thereby between said thermostat actuated lever and 5 said bearing member.

9. The combination with a water heater, of a burner therefor; a pilot for said burner; a water-actuated member; a thermostat connected to said heater; a fuel valve; a fuel 10 valve stem; a pilot valve on said fuel valve stem, arranged so that said pilot valve is opened to flash the pilot prior to the opening of said fuel valve; operating connections for said thermostat and water-actuated member 15 to said fuel valve stem, comprising a lever actuated by said thermostat, a pair of links, one of said links being connected to said fuel valve stem, and the other to a fixed support; a bearing member to which said links are 20 pivotally connected; and a member carried by said water actuated means to be reciprocated thereby between said thermostat actuated lever and said bearing member.

10. The combination with a water heater, 25 of a burner therefor; a water-actuated member; a thermostat connected to said heater; a fuel valve; a fuel valve stem; operating connections for said thermostat and water-actuated member to said fuel valve stem, comprising a lever actuated by said thermostat, a pair of links, one of said links being pivotally connected to said fuel valve stem, and the other to a fixed support; a bearing member to which said links are pivotally 30 connected; and a tapered member carried by said water actuated means to be reciprocated thereby between said thermostat actuated lever and said bearing member.

11. The combination with a water heater, 35 of a burner therefor; a water-actuated member; a thermostat connected to said heater; a fuel valve; a fuel valve stem; operating connections for said thermostat and water-actuated member to said fuel valve stem, comprising a lever actuated by said thermostat, a pair of links, one of said links being pivotally connected to said fuel valve stem, and the other to a fixed support; a bearing member to which said links are pivotally 40 connected; and a member carried by said water actuated means to be reciprocated thereby between said thermostat actuated lever and said bearing member.

12. The combination with a water heater, 45 of a burner therefor; a pilot for said burner; a water-actuated member; a thermostat connected to said heater; a fuel valve; a fuel valve stem; a pilot valve on said fuel valve stem, said fuel valve stem being provided 50 with a lost motion connection to said fuel valve whereby said pilot valve is opened to flash the pilot prior to the opening of said fuel valve; and operating connections for said thermostat and water actuated member

to said fuel valve stem, including a tapered 65 movable member through which said inlet valve and thermostat are each arranged to act.

13. The combination with a water heater, of a burner therefor; a pilot for said burners; 70 a water-actuated member; a thermostat connected to said heater; a fuel valve; a fuel valve stem; a pilot valve on said fuel valve stem, said fuel valve stem being provided with a lost motion connection to said fuel 75 valve whereby said pilot valve is opened to flash the pilot prior to the opening of said fuel valve; and operating connections for said thermostat and water actuated member to said fuel valve stem, including a movable 80 member through which said inlet valve and thermostat are each arranged to act.

14. The combination with a water heater, of a burner therefor; a pilot for said burner; 85 a water-actuated member; a thermostat connected to said heater; a fuel valve; a pilot valve; and operating connections for said thermostat and water-actuated member to said fuel and pilot valves, including a tapered 90 movable member on which said water-actuated member and thermostat are each arranged to act, said pilot and fuel valves being provided with a lost motion connection, whereby said pilot valve is opened prior to the 95 opening of the fuel valve.

15. The combination with a water heater, of a burner therefor; a pilot for said burner; a water-actuated member; a thermostat connected to said heater; a fuel valve; a pilot 100 valve; and operating connections for said thermostat and water-actuated member to said fuel and pilot valves, including a movable member on which said water-actuated member and thermostat are each arranged to act, said pilot and fuel valves being provided with a lost motion connection, whereby said pilot valve is opened prior to the opening of the fuel valve.

16. The combination with a water heater, of a burner therefor; a pilot for said burner; 110 a water-actuated member; a thermostat connected to said heater; a fuel valve; a pilot valve; and operating connections for said thermostat and water-actuated member to said fuel and pilot valves, including a toggle 115 on which said water-actuated member and thermostat are each arranged to act, said pilot and fuel valves being provided with a lost motion connection, whereby said pilot valve is opened prior to the opening of the 120 fuel valve.

17. The combination with a water heater, of a burner therefor; a pilot for said burner; a water inlet valve; a fuel valve; a fuel valve stem; a pilot valve on said fuel valve stem, 125 said fuel valve stem being provided with a lost motion connection to said fuel valve whereby said pilot valve is opened to flash

the pilot prior to the opening of said fuel valve; and operating connections for said water inlet valve to said fuel valve stem.

18. The combination with a water heater, 5 of a burner therefor; a pilot for said burner; a water-actuated member; a fuel valve; a pilot valve; and operating connections for said water-actuated valve to said fuel and pilot valves; said pilot and fuel valves being 10 provided with a lost motion connection

whereby said pilot valve is opened to flash the pilot prior to the opening of said fuel valve.

In witness whereof, I have hereunto set my hand and seal in the presence of two wit- 15 nesses.
